ELECTRIC SWITCH MECHANISM

Louis Ludwig, Brooklyn, N. Y.

Application June 30, 1936, Serial No. 88,083

3 Claims. (Cl. 173—355)

The invention relates to an electric switch of the push button type and has for its main object to provide a simple switch mechanism in which only a single push button is employed and which can be used with a great many electric devices, particularly those of the type which, by their nature, will indicate whether the switch is on or off, such for example as lamps, fans, and the like.

Another object is to provide a switch mechanism of simple construction which will occupy but small space, and which has no parts apt to wear out or get out of order. A further object is to provide a switch mechanism which can be manufactured and assembled at a low cost.

These and various other objects and advantages will be readily understood from the following description and from the accompanying drawing of preferred embodiments of the invention, in which, however, modifications may be made without departing from the scope of the appended claims.

In the drawing

Fig. 1 is a plan view of a switch made in accordance with the invention and shown with the switch open;

Fig. 2 is a similar view showing the switch ready to snap into the closed position;

Fig. 3 is a similar view shown with the switch in the closed position;

Fig. 4 is a cross-sectional side view of Fig. 1;

Fig. 5 is a top view showing the switch applied to a lamp socket;

Fig. 6 is a cross-sectional side elevation of Fig. 5;

Fig. 7 is another elevation of Fig. 5; and

Fig. 8 is a plan view of one of the parts used in the switch.

Figs. 1, 2, 3, and 4 illustrate a switch in which the mechanism is contained in a recess 10 formed in a body member 11, provided with sidewardly-extending flanges 12 by means of which the device may be secured to the fixture on which used.

A post 13, having an enlarged head 14, is secured to the body member in any suitable manner, as for example by threading its lower end and securing it by means of a nut 15. A switch lever 16 is pivoted on the post. This switch lever is formed of a piece of sheet metal bent substantially into U-shape and provided with an enlarged and transverse head 17 which is somewhat narrower than the lever itself. A washer 18 is slidably mounted on the legs of the switch lever and is provided with two slots 19 and 20, as plainly shown in Fig. 8.

A cam member 21 is also mounted on the post 13 and comprises two cam faces 22 and 23 which are formed substantially at right angles to each other. These two cam faces terminate in a peak 24 which is slightly rounded. The cam member is also provided with two notches 25 and 26 on the side opposite to the peak 24. It is mounted between the legs of the switch member so that either of the cam faces or the peak, engage against the space 27 left between the two slots 19 and 20 in the washer 18. This washer is held in contact with the cam member by means of a compression spring 28, the ends of which abut against the washer and the enlarged head 17.

A push button 29 is slidably mounted in the front of the body member and provided with a flexible bar 30 which is adapted to engage in either one or the other of the slots 25 and 26.

Spring terminals 31 and 32 are secured to the body member by means of screws 33 and 34. The wires to which the switch is connected are secured to these screws in the regular manner. The end of each of the terminals is provided with a contact member 35 and 36. These contact members are spaced apart so that a gap 37 is formed between them, as plainly shown in Fig. 4.

The switch operates in the following manner. As shown in Fig. 1, the switch is open. When the button 29 is pushed in, the flexible bar 30 engages in the notch 25 and turns the cam member in the direction and into the position shown in Fig. 2. In this view the peak 24 of the cam, as shown, coincides exactly with the center line 38 of the switch lever. A slight additional inward movement of the push button will cause the peak to pass beyond the center line and suddenly cause the switch lever to snap into the position shown in Fig. 3. When in this position the head 17 engages with the contact points 35 and 36 and thus closes the current.

When the pressure on the push button 29 is released, a compression spring 39, mounted between the push button and the head 14 of the post 13, restores the push button to its normal position. This spring has been omitted in Figs. 1 and 2. If the push button is now again pushed in the bar 30 will engage in the notch 26 to move the cam in the opposite direction and thus, after the peak 24 has passed the center line of the switch lever, cause the lever to snap over again to the position shown in Fig. 1, thus breaking the current. Stops 40 and 41 are formed in the recess to limit the movements of the switch lever.

In Figs. 5, 6, and 7, the switch is shown em-

ployed in a lamp socket. This socket comprises the body member 42 and the ordinary threaded metal shell 43 which is separated from the body member by an insulating washer 44. The parts are secured together by means of screws 45 and 46. Inasmuch as the switch mechanism itself is identical with the switch mechanism just described, the various parts have been numbered similarly to the part just described. The only difference is that the spring terminal 31 is provided with an upwardly-extending contact member 47 which constitutes the center contact of the lamp socket; the shell constituting the other terminal as in the ordinary lamp socket. The screw 45 is secured in a wire clamp 48, to which one of the wires associated with the socket may be connected, while the other wire may be connected to a wire clamp 49 secured to the screw 32. The hole in the terminal 31 is sufficiently large so that the screw 45 does not touch the terminal. The screw 46 is only employed for clamping the shell, the washer and the body part together. This switch operates in the same manner as the one previously described.

While I have described and illustrated the switch mechanism in connection with certain fixtures, it is, of course, evident that a switch mechanism of this kind may be employed in many other fixtures and constructed with certain modifications to adapt it to such fixtures. I do not therefore, wish to limit myself to the exact embodiments shown, but intend to use the switch mechanism for any purposes to which it is adaptable.

Having described the invention and its objects, what I claim as new and wish to protect by Letters Patent is:—

1. A switch mechanism comprising a recessed lamp-socket base; a post secured in the recess in said base; a bifurcated switch lever rotatably mounted on said post; an angular cam member similarly mounted on said base and in the bifurcation of said switch lever; a washer slidably mounted on the switch lever and engaged against the cam member; a compression spring associated with the switch lever for normally holding said washer in contact with one or the other of the faces on said cam member; two angular notches formed in the cam member; spaced contact members secured in the recess; one of said contact members provided with an upwardly-extending member forming the center-contact for the lamp socket; an apertured insulating washer for covering said recess; a metal screw shell secured to said washer and base; a push button slidably mounted laterally in the base and extending outside thereof; a flat spring member associated with said push button for engaging in one or the other of the said notches to turn the cam member; and a peak formed on the cam member which when passing beyond the axial center line of the switch lever will cause this to be snapped in one direction or the other, by the action of the compression spring and the washer associated with the switch lever, to engage with or disengage from said contact members according to which notch is being engaged.

2. A switch mechanism comprising a recessed lamp socket base; a post secured in the recess in said base; a bifurcated switch lever rotatably mounted on said post; an angular cam member similarly mounted on said base and in the bifurcation of said switch lever; a washer slidably mounted on the switch lever and engaged against the cam member; a compression spring associated with the switch lever for normally holding said washer in contact with one or the other of the faces on said cam member; two angular notches formed in the cam member; spaced contact members secured in the recess; one of said contact members provided with an upwardly-extending member forming the center-contact for the lamp socket; an apertured insulating washer for covering said recess; a metal screw shell secured to said washer and base; a push button slidably mounted laterally in the base and extending outside thereof; means for restoring said push button to its normal position; a flat spring member associated with said push button for engaging in one or the other of the said notches to turn the cam member; and a peak formed on the cam member which when passing beyond the axial center line of the switch member will cause this to be snapped in one direction or the other, by the action of the compression spring and the washer associated with the switch lever, to engage with or disengage from said contact members according to which notch is being engaged.

3. A switch mechanism comprising a recessed lamp-socket base; a post secured in the recess in said base; a bifurcated switch lever rotatably mounted on said post; an angular cam member similarly mounted on said base and in the bifurcation of said switch lever; a washer slidably mounted on the switch lever and engaged against the cam member; a compression spring associated with the switch lever for normally holding said washer in contact with one or the other of the faces on said cam member; two angular notches formed in the cam member; spaced contact members secured in the recess; one of said contact members provided with an upwardly-extending member forming the center-contact for the lamp socket; an apertured insulating washer for covering said recess; a metal screw shell secured to said washer and base; a push button slidably mounted laterally in the base and extending outside thereof; means for restoring said push button to its normal position; a flat spring member associated with said push button for engaging in one or the other of the said notches to turn the cam member; a peak formed on the cam member which when passing beyond the axial center line of the switch lever will cause this to be snapped in one direction or the other, by the action of the compression spring and the washer associated with the switch lever, to engage with or disengage from said contact members according to which notch is being engaged.

LOUIS LUDWIG.
